UNITED STATES PATENT OFFICE.

GEORGE H. EMERY, OF PORTSMOUTH, NEW HAMPSHIRE.

CURTAIN-HANGER.

1,053,796.

Specification of Letters Patent.

Patented Feb. 18, 1913.

Application filed March 29, 1912. Serial No. 687,127.

To all whom it may concern:

Be it known that I, GEORGE H. EMERY, a citizen of the United States, residing at Portsmouth, in the county of Rockingham 5 and State of New Hampshire, have invented new and useful Improvements in Curtain-Hangers, of which the following is a specification.

This invention relates to curtain hangers, 10 the object in view being to provide a simple, practical and easily applied device of the character specified, made as an entirety from a single sheet metal blank bent and fashioned into shape to provide supporting and 15 attaching means and also supporting means for a curtain, shade roller, portière or other form of curtain, together with means for gradually arresting the too rapid revolution of the shade roller as the shade is 20 wound thereon.

With the above and other objects in view, the nature of which will more fully appear as the description proceeds, the invention 25 consists in the novel construction, combination and arrangement of parts herein fully described, illustrated and claimed.

In the drawings, Figure 1 is a front elevation of the upper portion of a window casing illustrating two of the improved hangers 30 applied thereto. Fig. 2 is a perspective view of one of the hangers. Fig. 3 is an end view thereof, also illustrating a shade roller and shade in cross section. Fig. 4 is a rear elevation of the fixture, showing the 35 form of the retaining prongs.

The fixture or hanger contemplated in this invention is constructed of sheet metal of requisite gage to impart the necessary 40 rigidity thereto and also to provide for the flexibility of the check which arrests the too rapid rotation of the shade roller, as will hereinafter appear.

The blank is bent along the longitudinal line 1 to provide the main depending body 45 portion 2 and a backwardly extending flange 3 designed to rest upon the top of the window casing and support the hanger thereon. The flange 2 is cut or punched as shown at 4 and small portions of the flange bent downward to form impaling prongs 5 which are 50 driven into the top of the window casing by striking upon the flange 1 with a hammer or similar implement. The body portion 2 is

provided with a pendent lip 6 provided with a hole 7 to receive a nail, screw or like fastener adapted to be driven into the front of the window casing to prevent any possibility of the hanger becoming detached from the window frame. 55

One corner of the blank is bent along the line 8 and extended forward to form a supporting ear 9 having a hole 10 having the end journal on the curtain shade roller. Just above the ear 9 the blank is bent at 11 and extended forward to form a projecting 60 supporting arm or bracket 12 terminating in an upwardly opening hook 13 designed to receive a rod or other form of support for a portière or lace curtain. At the opposite lower corner of the body, the latter is bent 70 at 14 and also curved to form an arched or substantially semi-circular spring arm 15 terminating in an upwardly turned extremity 16, said spring arm being adapted to bear against the curtain shade as it winds upward on the roller supported by the ear 9, whereby as the curtain shade increases in size as it winds upon the roller, the spring arm acts as a yielding check which frictionally bears against the curtain shade as it surrounds the roller and gradually takes up and reduces the speed of said roller, thereby preventing injury to the curtain shade when it slips out of the fingers in adjusting the curtain, as frequently happens. 75

I claim:—

As an article of manufacture, a one-piece curtain hanger and friction brake, consisting of a sheet metal blank bent to comprise a rearwardly extending flange adapted to 90 rest on top of the window casing, prongs punched in the body of the flange and adapted to be driven into the window casing, a curtain supporting bracket arm at one end of the body, and an integral spring 95 check at the opposite end of the body curved to partially surround the curtain roll and frictionally resist the winding of the shade on the roller.

In testimony whereof I affix my signature 100 in presence of two witnesses.

GEORGE H. EMERY.
